UNITED STATES PATENT OFFICE.

HENRY A. THEXTON, OF MINNEAPOLIS, MINNESOTA, ASSIGNOR, BY DIRECT AND MESNE ASSIGNMENTS, TO THEXTON STAMP-VENDING MACHINE COMPANY, OF MINNEAPOLIS, MINNESOTA, A CORPORATION OF MINNESOTA.

VENDING-MACHINE.

No. 911,091.

Specification of Letters Patent.

Patented Feb. 2, 1909.

Application filed June 3, 1907. Serial No. 377,060.

To all whom it may concern:

Be it known that I, HENRY A. THEXTON, of Minneapolis, Hennepin county, Minnesota, have invented certain new and useful 5 Improvements in Vending - Machines, of which the following is a specification.

The object of my invention is to provide a machine capable of vending various articles but designed particularly for delivering postage stamps contained within a suitable envelop.

Postage stamps are kept for sale by news stands and drug stores merely as an accommodation to their customers and when the 15 clerks are busy the person desiring a stamp, as for instance, a traveler at a hotel, is obliged to wait some time before receiving attention.

It is my object therefore to provide a suitable receptacle containing envelops which the clerks may supply with stamps during their leisure moments so that a patron or customer can, by the deposit of a coin in the receptacle, obtain the desired number of 25 stamps without any attention whatever on the part of the clerks.

The invention consists generally in various constructions and combinations, all as hereinafter described and particularly pointed 30 out in the claims.

In the accompanying drawings, forming part of this specification, Figure 1 is a vertical sectional view of a vending machine embodying my invention, illustrating the coin 35 deposited in the machine and the mechanism ready to deliver the envelop. Fig. 2 is a sectional view of the lower portion of the machine showing the mechanism when it has completed its forward stroke and the edge 40 of the envelop has been projected from the machine. Fig. 3 is a horizontal sectional view on the line $x-x$ of Fig. 1. Fig. 4 is a similar view on the line $y-y$ of Fig. 1. Fig. 45 5 is a detail view of the envelop feeding device.

In the drawing, 2 represents a suitable base on which a casing, composed of side walls 3, rear and front walls 4 and 5 and a top 6, is mounted. Suitable glass panels 7, 8 and 9 50 are provided through which the contents of the case are visible. The top 6 has a hinged section 6' through which access may be had to the interior of the case for filling it with

envelops and removing the coins. The front wall 5 has a slot 10 through which the edges 55 of the envelops containing the stamps are projected. Mounted on the base 2 is a support 11 for a sliding plate 12. The support and plate have openings 13 and 14 which normally do not register with one another, the 60 latter being beneath the discharge end of a coin chute 15 which extends through the top of the machine and has an open upper end into which the coin is inserted. The lower end of the chute is curved so that the coin 65 will be delivered horizontally, and as it passes out of the chute it falls into the opening 14 and rests upon the top of the support 11. An arm 16 is mounted on a rock shaft 17 and has a notch 18 in its lower end that is 70 adapted to receive the edge of the coin inserted into the chute, the opposite side of the coin bearing on the edge of the sliding plate 12 so that when the arm 16 is oscillated after the deposit of a coin the sliding plate will be 75 moved also. The shaft 17 is provided with an operating handle 19 and the arm 16 is held in a retracted position against a stop 20 by a spring 21. A lug 22 is provided on the lower end of the arm 16 in position to engage 80 the rear end of the sliding plate and cause the continued forward movement of said plate after the coin has passed out of contact with the forward edge of said arm. This lug also strikes the fixed support 11 and limits the 85 movement of the arm in one direction. The forward end of the plate 12 is provided with arms 23 spreading laterally from said plate in the form of a Y and adapted to engage the loose flap of an envelop that is placed on the 90 plate with the flap on the under side as indicated in Fig. 1. The envelops are placed in the machine one upon another and fed from the bottom, the pile dropping by gravity as fast as the envelops are discharged, so that there will always be one with a depending flap in the path of the feed plate when it is projected forward.

I prefer to provide a weight 23' upon the pile of envelops to insure a continuous downward feed thereof as fast as the bottom one is fed out of the pile.

The discharge slot through which the envelops are delivered is normally covered by a sliding plate 24 that is adapted to move vertically between guides 25, and is carried by 105

an arm 26 pivoted at 27 on a bracket 28. A spring 29 normally holds the said arm in its raised position and the plate 25 across the discharge slot to prevent anyone from tampering with the machine and removing an envelop without the deposit of a coin. An arm 30 is carried by the sliding plate and provided with a beveled edge 31 in position to contact with a cam surface 32 on the arm 26, so that when the said plate is projected the arm 26 will be depressed to force the plate 24 downwardly and expose the discharge slot. A pin 33 is mounted in the arm 26 and a finger 34 carried by the plate 12 depends in position to pass under the pin 33 and lock it and the said arm against premature depression, or until such time as the plate 12 is projected forward after the deposit of a coin. A spring 35 is connected to the sliding plate and to a fixed pin for the purpose of withdrawing said plate after the discharge of the envelop, and returning the parts to their normal position.

To operate the device the customer will deposit a coin, for instance a five-cent piece, in the chute and it will slide down therein and be discharged in a horizontal position upon the support near said chute, and between the recess 18 and the edge of the feed plate. The deposit of this coin will close temporarily the break between the arm 16 and the edge of the feed plate and cause the said plate to be moved forward when the arm is oscillated. The forward movement of the said plate will cause its Y-shaped end to engage the loose flap of the bottom envelop and feed it forward. The forward movement of the feed plate will actuate the arm 30 and its beveled end will cause the depression of the arm 26 and open the discharge slot of the machine just at the time the envelop is moved forward and is about to enter the said slot. When the envelop has been projected through the slot the customer will grasp it and draw it out from beneath the others and upon releasing the operating lever the springs will return the feed plate and the oscillating arm to their normal position and the plate 24 will slide upwardly past the discharge slot and prevent a second envelop from being withdrawn, and the finger 34 passing beneath the pin 33 will lock the plate 24 and the arm 26 in their raised position and positively prevent depression thereof and unauthorized access to the envelops until the gap between the arm 16 and the edge of the feed plate has been closed by the deposit of another coin. In this way a pile of envelops can be fed out of the machine one at a time and in these envelops postage stamps aggregating preferably five cents in value may be placed. For instance, two two-cent stamps and a one-cent stamp may be placed in each envelop, or in a great many instances, a

person in a hurry, or a traveler, will frequently pay five cents for two two-cent stamps and have them delivered immediately out of a machine, rather than wait to receive the change from a clerk. Where only four cents worth of stamps are placed in the envelop a notice would preferably be placed on the machine to the effect that upon the deposit of a five-cent coin two two-cent stamps will be delivered. The placing of the stamps in the envelops, however, of equal or less value to the coin deposited, will be optional with the person having charge of the machine and generally will be determined by the place where the machine is used.

The envelops will be made of suitable size to carry the stamps conveniently and may be used as a cover for such stamps as are not required immediately at the time of operation of the machine.

I claim as my invention:

1. In a machine of the class described, the combination, with a support, of a feed plate slidable thereon, an oscillating actuating means for said plate, said support being adapted to receive a coin deposited between said plate and said actuating means, said means moving in the arc of a circle and having a forward portion on its initial movement engaging the coin and forcing it against said plate to project the same and said means passing out of engagement with the coin and the coin being released and discharged after said initial movement, and said actuating means having a rear portion that engages said plate and completes the stroke of the same after the release of the coin, substantially as described.

2. The combination, with a horizontal guide or support, of a horizontal feed plate slidably mounted thereon and having an opening to receive a coin, and said guide normally forming the bottom for said opening and supporting the coin in a horizontal position therein, and having a discharge opening in advance of the part upon which the coin is deposited an actuating means arranged to engage the rear edge of the coin and force its forward edge against said feed plate to project the same, the coin dropping by gravity through said discharge opening from between said actuating means and feed plate at a predetermined point after the initial movement of said actuating means and said actuating means having a part that engages said feed plate and completes its stroke after the release of said coin.

3. In a machine of the class described, the combination, with a support or guide, of a feed plate slidably mounted thereon, and having an opening to receive a coin deposited flat-wise upon said guide, an oscillating actuating means arranged to engage the rear edge of the coin and force its forward edge

against said feed plate to project the same, said guide having a discharge opening through which said coin drops by gravity from its horizontal position at a predetermined point in the travel of said feed plate and said actuating means moving on the arc of a circle and passing out of contact with the coin when it registers with said discharge opening.

10 4. In a machine of the class described, the combination, with a support, or guide, of a feed plate or plunger thereon, an oscillating arm between which and said feed plate the coin is deposited flatwise, said arm during its initial movement contacting with the rear edge of said coin and the forward edge of said coin engaging said feed plate to project the same, said arm swinging on the arc of a circle and moving out of contact with said coin 20 after its initial movement and permitting the release of the coin and said arm having a part to engage the said plate after the release of the coin to complete the stroke of the plate.

25 5. In a machine of the class described, the combination, with a support or guide, of a feed plate operating thereon, an oscillating arm between which and said feed plate the coin is deposited in a horizontal position, said arm on its initial movement engaging the coin to move said feed plate and said arm out of engagement with said coin and releasing it after the initial movement of said arm and plate, and said arm having a lug 30 normally out of contact with said feed plate but adapted to engage and complete the stroke of said plate when the coin has been released.

6. In a machine of the class described, a support having a coin discharge opening, a feed plate or plunger operating thereon and also having a coin opening, an oscillating arm between which and said feed plate the coin is deposited upon said support, said arm on its initial movement engaging the edge of the coin and forcing it against said feed plate to move the same, and said coin dropping down from between said feed plate and arm when it passes over the coin discharge opening in said support, and said arm having means to engage and complete the stroke of said feed plate after the discharge of the coin, substantially as described.

7. In a vending machine, the combination, with a support having a coin discharge opening, of a feed plate arranged to slide back and forth on said support and also having an opening to receive the coin in a horizontal position, the coin opening in

said feed plate in its retracted position being 60 out of register with the opening in said support, a coin chute adapted to deliver the coin to the opening in said feed plate, an actuating means arranged to engage the rear edge of the coin and force its forward edge 65 against said feed plate to project the same, said actuating means releasing the coin and permitting it to drop through the discharge opening in said support when the opening in said feed plate registers with the opening in 70 said support, and said actuating means having a part to engage said feed plate and complete the stroke of the same after the release of the coin.

8. In a vending machine the combination, with a support having a coin discharge opening, of a feed plate arranged to slide back and forth on said support and also having an opening to receive the coin in a horizontal position, the coin opening in said feed plate in its retracted position being out of register with the opening in said support, a coin chute adapted to deliver the coin to the opening in said feed plate, an oscillating arm having a forward edge adapted to engage the rear edge of the coin and force it against said feed plate to project the same, said forward edge moving out of contact with the coin to permit its discharge when the opening in the feed plate registers with 90 the opening in said support, and the rear edge of said arm having a part to engage said feed plate and complete the stroke of the same when said coin has been released.

9. The combination, with a support, of a feed plate slidable thereon, an actuating means for said plate, said support being adapted to receive a coin deposited between said plate and said actuating means, said actuating means swinging on the arc of a 100 circle and having a forward edge adapted to engage the rear of a coin and force it against said feed plate to project the same, said forward edge moving out of contact with the coin after the initial movement of said 105 actuating means and permitting the release and discharge of the coin from between said actuating means and feed plate and the rear portion of said actuating means having a part to engage said feed plate to complete 110 the stroke of the same after the release of the coin.

In witness whereof, I have hereunto set my hand this 1st day of June 1907.

HENRY A. THEXTON.
